United States Patent Office

Des. 229,386

Patented Nov. 27, 1973

229,386

MIRROR

Sven-Eric Juhlin, Gustavsberg, Sweden, assignor to
AB Gustavsbergs Fabriker, Gustavsberg, Sweden

Filed May 5, 1972, Ser. No. 250,859

Term of patent 14 years

Int. Cl. D6—07

U.S. Cl. D6—242

1 H 1 FIG. 1 is a front elevational view of a mirror showing my new design.

FIG. 2 is a right side elevational view.

FIG. 3 is a top plan view thereof.

FIG. 4 is a rear elevational view thereof.

FIG. 5 is a right cross sectional view thereof taken on line 5-5 of FIG. 1.

FIG. 6 is a front perspective view thereof.

I claim:

The ornamental design for a mirror, as shown.
